UNITED STATES PATENT OFFICE

100,033

DESIGN FOR A GAME BOARD

Lester Levy, San Francisco, Calif.

Application March 17, 1936, Serial No. 61,673

Term of patent 3½ years

To all whom it may concern:

Be it known that I, Lester Levy, a citizen of the United States, residing in the city and county of San Francisco and State of California, have invented a new, original, and ornamental Design for a Game Board, of which the following is a specification, reference being had to the accompanying drawing, forming a part thereof.

In the accompanying drawing:

The figure is a plan view of a game board embodying my invention.

The game board comprising the present invention is flat and of no appreciable thickness.

I claim:

The ornamental design for a game board as shown and described.

LESTER LEVY.
